(57) **CLAIM**

The ornamental design for an exterior of tank for installation on truck chassis as shown and described.

DESCRIPTION

FIG. 1 is a top, side and front perspective view of an exterior of tank for installation on truck chassis embodying our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is bottom, side and front view thereof.

The broken lines in the drawings illustrate portions of the exterior of tank for installation on truck chassis that form no part of the claimed design.

1 Claim, 7 Drawing Sheets
